HAIR CLIPPER

Anthony P. Ferraro, East Rutherford, N. J.

Application July 21, 1953, Serial No. 369,394

3 Claims. (Cl. 30—29.5)

1

This invention relates to electrically operated hair clippers and more particularly to a small clipper especially designed to clip superfluous hair in restricted spaces, such as the nostrils and ears.

It is among the objects of the invention to provide an improved hair clipper which is electrically actuated and of such small size and light weight that it can be easily held and manipulated by the fingers of one hand of a person using the device; which has at one end thereof a clipper head shaped and dimensioned for easy insertion into the ears or nostrils for clipping superfluous hair therefrom; which has a slotted tongue laterally movable in the hollow, slotted clipper head so that the tongue slots are moved across the head slots to provide a scissor-like clipping action; and which is simple and durable in construction, economical to manufacture, easy to use, and neat and attractive in appearance.

Other objects and advantages will become apparent from a consideration of the following description and the appended claims in conjunction with the accompanying drawing, wherein:

Figure 1 is a side elevational view of a clipper illustrative of the invention with a portion broken away and shown in cross section to better illustrate the construction thereof;

Figure 2 is a longitudinal cross sectional view on the line 2—2 of Figure 1; and

Figure 3 is an end elevational view of the head end of the clipper.

With continued reference to the drawing, the clipper comprises a hollow casing 10 of elongated shape and formed of a suitable material, such as a synthetic resin plastic. One end of the casing is closed by a flat end wall 11 and the other end is open and provided with an internal flange formation 12 providing a groove 13 of circular shape extending around and opening to the open end of the casing. A sleeve 14 of cylindrical shape has one end inserted in and secured in the groove 13 and constitutes, in effect, an elongation of the casing 10 at the open end of the casing.

An electrically actuated, vibratory motor is disposed in the casing 10 and comprises an electro-magnet 15 mounted at one end on the casing by an elongated, resilient bracket 16, the bracket being secured at its ends to the inner side of the casing side wall and bowed intermediate its length away from the casing side wall and the electro-magnet 15 being secured at one end on the bracket 16 intermediate the length of the bracket. The electro-magnet 15 has a core 17 one end of

2

which extends from the end of the magnet remote from the bracket 16 and has a winding 18 surrounding the core and provided with terminals 19 and 20. A two wire extension cord 21 extends through a centrally disposed aperture in the end wall 11 of the casing and has one wire 22 thereof connected to the terminal 19 of the electro-magnet.

An arm 23 is mounted at one end on the bracket 16 and extends past the electro-magnet 15 in spaced relationship thereto and an armature 24 is pivotally mounted at one end on the arm 23 at a location spaced from the bracket 16 and extends past the projecting end of the core 17 of the electro-magnet. A resilient switch 25 is disposed between the armature 24 and the electro-magnet and the armature carries a pin 26 which engages and opens the switch when the armature is drawn toward the core of the electro-magnet. One side of the switch is connected to the other terminal 20 of the electro-magnet by a conductor 27 and the other side of the switch is connected to the other wire 28 of the two wire extension cord 21.

With this arrangement, when the extension cord 21 is connected to a source of electrical energy, the switch 25 being closed and the armature 24 being held away from the electro-magnet core by the switch, the electro-magnet will be energized drawing the armature to the magnet core and opening the switch which de-energizes the magnet and releases the armature for movement back to its normal position. This causes the armature 24 to vibrate back and forth in the well known manner of door-bell or buzzer motors about its pivotal connection with the arm 23.

A hollow, thin-walled cap 30, preferably of circular cross sectional shape, has one open end receiving the sleeve 14 and releasably secured on the sleeve by a detent and dimple formation 31. The other end of the cap is closed and is flattened, as illustrated in Figure 1, to provide spaced apart and substantially parallel flat walls 32 and 33 and is outwardly tapered in width, as indicated at 34, to provide a curved side wall 35 extending marginally around the side walls 32 and 33 and disposed substantially perpendicular thereto. This flattened end portion of the cap is provided with spaced apart and substantially parallel slots 36 extending through the side wall 35 and both of the flat walls 32 and 33 longitudinally of the cap and constitutes a hollow, clipper head.

An elongated tongue 38 is connected at one end to the end of the armature 24 nearest the open end of the casing 10 and extends through

the sleeve 14 and the hollow cap 30. At its end remote from the armature 24 this tongue 38 is provided with a flattened formation 40 of a width somewhat greater than the width of the remainder of the tongue and having convexly rounded side edges. This flattened formation has a thickness substantially equal to the distance between the inner surfaces of the flat walls 32 and 33 of the clipper head and has a width materially less than the width of the head and is tapered in width from its intermediate length portion toward both of its ends. The formation 40 is provided with spaced apart and substantially parallel slots 41 extending through the thickness of the formation and longitudinally of the tongue and, when the armature 24 is vibrated back and forth in the manner explained above, the flat formation 40 of the tongue is moved back and forth across the width of the clipper head so that the slots 41 in the terminal formation 40 of the tongue move across the slots 36 in the wall of the clipper head and provide a scissor-like clipping action. The clipped hairs fall into the hollow cap 30 from which they can be removed when desired by removing the cap from the sleeve 14 by means of which the cap is mounted on the casing 10.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A hair clipper comprising a hollow casing of elongated shape having one open end, a sleeve extending longitudinally from the open end of the casing, an electrically actuated vibratory motor mounted in said casing and having a pivotally supported armature extending longitudinally of the casing, a tubular cap having an open end receiving said sleeve and having its other end closed and flattened and tapered outwardly in width and provided with spaced apart slots extending longitudinally of the cap to provide a hollow clipper head, and a tongue extending through said cap and said sleeve and connected at one end to the adjacent end of said armature, said tongue having at its other end a flattened terminal formation movable laterally within said head and provided with spaced apart slots extending through the thickness of said

formation and longitudinally of said tongue and movable across the slots in said head to provide a scissor-like clipping action.

2. A hair clipper comprising a hollow casing of elongated shape having one open end, an electrically actuated vibratory motor mounted in said casing and having an armature extending longitudinally of the casing and pivotally supported at its end adjacent the closed end of the casing, a tubular cap having an open end mounted at its open end on the open end of said casing and having its other end closed and flattened and tapered outwardly in width and provided with spaced apart slots extending longitudinally of the cap to provide a hollow clipper head, and a tongue extending through said cap and connected at one end to the adjacent end of said armature, said tongue having on its other end a flattened terminal formation movable laterally within said head and provided with spaced apart slots extending through the thickness of said formation and longitudinally of said tongue and movable across the slots in said head to provide a scissor-like clipping action.

3. A hair clipper comprising a hollow casing of elongated shape having one open end, an electrically actuated vibratory motor mounted in said casing and having an armature extending longitudinally of the casing and pivotally supported at its end adjacent the closed end of the casing, a tubular cap having an open end mounted at its open end on the open end of said casing and having its other end closed and flattened and tapered outwardly in width and provided with spaced apart slots extending longitudinally of the cap to provide a hollow clipper head, and a tongue extending through said cap and connected at one end to the adjacent end of said armature, said tongue having on its other end a flattened terminal formation movable laterally within said head and provided with spaced apart slots extending through the thickness of said formation and longitudinally of said tongue and movable across the slots in said head to provide a scissor-like clipping action.

4. A hair clipper comprising a hollow casing of elongated shape having one open end, an electrically actuated vibratory motor mounted in said casing and having an armature extending longitudinally of the casing and pivotally supported at its end adjacent the closed end of the casing, a tubular cap having an open end mounted at its open end on the open end of said casing and having its other end closed and flattened and tapered outwardly in width and provided with spaced apart slots extending longitudinally of the cap to provide a hollow clipper head, and a tongue extending through said cap and connected at one end to the adjacent end of said armature, said tongue having on its other end a flattened terminal formation movable laterally within said head and provided with spaced apart slots extending through the thickness of said formation and longitudinally of said tongue and movable across the slots in said head to provide a scissor-like clipping action.

5. A hair clipper comprising a hollow casing of elongated shape having one open end, an electrically actuated vibratory motor mounted in said casing and having an armature extending longitudinally of the casing and pivotally supported at its end adjacent the closed end of the casing, a tubular cap having an open end mounted at its open end on the open end of said casing and having its other end closed and flattened and tapered outwardly in width and provided with spaced apart slots extending longitudinally of the cap to provide a hollow clipper head, and a tongue extending through said cap and connected at one end to the adjacent end of said armature, said tongue having on its other end a flattened terminal formation movable laterally within said head and provided with spaced apart slots extending through the thickness of said formation and longitudinally of said tongue and movable across the slots in said head to provide a scissor-like clipping action.
